(57) **CLAIM**

The ornamental design for a necklace, as shown and described.

DESCRIPTION

FIG. 1 is a front view of a necklace of my new design; FIG. 2 is a rear view thereof;

FIG. 3 is a right perspective view thereof;

FIG. 4 is a left perspective view thereof;

FIG. 5 is a top perspective view thereof;

FIG. 6 is a bottom perspective view thereof;

FIG. 7 is a front right perspective view thereof;

FIG. 8 is a rear left perspective view thereof;

FIG. 9 is an enlarged front view of the central element of the necklace shown in FIG. 1; and,

FIG. 10 is an enlarged front right perspective view of the central element of the necklace shown in FIG. 7.

The dot-dash broken lines represent the designation of enlargement views and form no part of the claimed design.
